UNITED STATES PATENT OFFICE.

HENRY MACARTHY, OF NEW YORK, ASSIGNOR TO S. A. HSLEY & CO.,
OF BROOKLYN, NEW YORK.

DESIGN FOR A METAL BOX.

SPECIFICATION forming part of Design No. 25,097, dated January 28, 1896.

Application filed September 23, 1895. Serial No. 563,446. Term of patent 7 years.

To all whom it may concern:

Be it known that I, HENRY MACARTHY, a citizen of the United States, residing at New York, in the county of New York and State of New York, have invented a new Design 5 for a Metal Box, of which the following is a specification.

This design relates to a round metal box, and the leading feature consists of a conical 10 top having a central cylindrical neck with a peripheral rib around the middle portion of such cylindrical neck.

In the accompanying drawings this design is represented by the section, Figure 1, and 15 perspective view, Fig. 2.

The box B is cylindrical, with an offset-rib 1 around its upper edge, a conical top A, and a neck C, the surface of which is cylindrical at 4, with a peripheral rib 5 midway of the cylindrical portion 4. The top surface of the 20 neck is substantially flat and perforated.

I claim—

The design for a metal box as described and shown.

Signed by me this 16th day of September, 25 1895.

HENRY MACARTHY.

Witnesses:

GEO. T. PINCKNEY,
S. T. HAVILAND.
